CLAIM

The ornamental design for an electronic module for a tank lid, as shown and described.

DESCRIPTION

FIG. 1 is a top perspective view of an embodiment of an electronic module for a tank lid showing our new design; FIG. 2 is a front view of the electronic module for a tank lid illustrated in FIG. 1;

FIG. 3 is a rear view of the electronic module for a tank lid illustrated in FIG. 1;

FIG. 4 is a left side view of the electronic module for a tank lid illustrated in FIG. 1;

FIG. 5 is a right side view of the electronic module for a tank lid illustrated in FIG. 1;

FIG. 6 is a top view of the electronic module for a tank lid illustrated in FIG. 1; and,

(Continued)

FIG. 7 is a bottom view of the electronic module for a tank lid illustrated in FIG. 1. The broken lines in the drawings depict portions of the electronic module for a tank lid and form no part of the claimed design.

1 Claim, 4 Drawing Sheets
